UNITED STATES PATENT OFFICE.

FRANK LESLIE RICHARDSON, OF MANIFEST, LOUISIANA.

ENVELOP.

No. 882,843.

Specification of Letters Patent. Patented March 24, 1908.

Application filed October 5, 1907. Serial No. 336,692.

To all whom it may concern:

Be it known that I, FRANK LESLIE RICHARDSON, a citizen of the United States, residing at Manifest, in the parish of Catahoula and State of Louisiana, have invented certain new and useful Improvements in Envelops, of which the following is a specification.

This invention relates to safety envelops, designed to be employed for protection of the contents, and preventing surreptitious opening of the envelop, and has for its object to provide a simply constructed device of this character which will effectually protect the contents and prevent the opening of the envelop by unauthorized persons without this operation being observed by the receiver of the envelop.

With these and other objects in view, the invention consists in certain novel features of construction and arrangement of parts as hereinafter shown and described and specifically pointed out in the claims.

In the drawings employed for illustrating the invention is shown the preferred form of embodiment of the same, and in these drawings:—Figure 1 is a view of the blank from which the envelop is constructed. Fig. 2 is a view of the envelop complete and folded and sealed. Fig. 3 is an enlarged section on the line 3—3 of Fig. 2. Fig. 4 is a perspective view, enlarged, of the metal securing device detached. Fig. 5 is a sectional detail enlarged view of the safety locking portion of the securing device. Fig. 6 is a perspective view of the improved envelop in position ready to receive its contents. Fig. 7 is a perspective view taken from the side opposite to that shown in Fig. 6, with the securing flap thrust through the slit in the body of the envelop, showing the position of the latter just prior to the insertion therethrough of the securing device.

The improved envelop is constructed from a single sheet of paper in the form shown in Fig. 1, comprising a main body portion with two oppositely extending lateral flaps intermediate its ends with one end of the sheet having its sides converging and with the other end of the sheet reduced in size.

The central portion of the sheet from which the envelop is constructed is indicated at 10 and the lateral flaps at 11—12 extending from the ends of the central portion 10, the portion 10 forming one side of the pocket or letter receiving portion of the envelop

when the latter is folded. At opposite sides of the portion 10 are flaps 13—14 of substantially the same size as the portion 10, a slit 15 being formed between the portion 10 and the flap 13. Extending from the outer side of the flap 13 is the portion having the converging sides above mentioned which is in two parts 16 and 17, the part 17 adapted to be folded upon the part 16 along the dotted line 18, to increase the thickness of the material at this point, as hereafter explained. Extending from the outer side of the flap 14 is the reduced portion above mentioned and is also divided into two parts 19—20 by a dotted line 21, the part 20 adapted to be folded upon the part 19 at the dotted line.

The portion 10 is provided with spaced elongated apertures 22—23, while the portion 16 is provided with similar apertures 24—25, the portion 17 provided with similar apertures 26—27, the portion 19 provided with similar apertures 28—29 and the portion 20 provided with similar apertures 30—31. The apertures 24—26 and 25—27 are in alinement when the portion 27 is folded upon the portion 16, as indicated in Fig. 6, and the apertures 28 and 30 and 29—31 are respectively in alinement when the portion 20 is folded upon the portion 19, as indicated in Figs. 6 and 7. These several series of apertures are designed to receive a metal fastening device illustrated in Fig. 4 and consisting of a strip of ductile metal 32 bent into a U-form with the arm portions adapted to be passed first through the apertures 22—23, thence consecutively through the apertures 28—30 and 29—31 and then through the apertures 24—26 and 25—27, as indicated in Figs. 6 and 7. One of the arms of the fastening device 32 is provided with oppositely extending oblique points 33 of arrow shape, while the terminal of the other arm is provided with a socket 34 having an enlarged inner portion 35 and a contracted throat or entrance 36, so that when the barbed or arrow-shaped end of one arm is thrust into the enlarged interior 35 of the head 34, the inner ends of the barbs will catch behind the points 37 within the head and be retained thereby. It will be understood that the points 33 are sufficiently resilient to be contracted as they pass through the narrow throat 36 and then expand in the rear of the portions 37, and be thus locked in position, as will be obvious.

In arranging the envelop for use the flap 14 is folded over upon the flap 10 along the line 38 and the flaps 11-12 folded over the flap 14 with their ends overlapping, the flaps 11-12 being gummed, as indicated at 39-40, so that when the flaps 11-12 are folded over the flap 14 their lower edges may be gummed to the outer surface of the flap 14, the flap 12 being also gummed, as at 41, 10 so that when the outer ends of the flaps 11-12 are overlapped they can be secured by gumming, as will be obvious. The portion 17 is then folded over upon the portion 16 and gummed thereto. This will dispose 15 the envelop in condition for receiving its contents, as shown in Fig. 6, and after the contents are disposed in the pocket between the portion 10 and the flap 14, the reduced folded portion 19-20 is doubled over partly upon 20 itself and its free end thrust through the slit 15, which causes it to project beyond the portion 10, as shown in Fig. 7. The reduced portion 19-20 thus forms a partial closure and protection to the contents of the envelop. 25 The member 32, when first inserted through the portion 10, is left with its arms projecting at right angles to the body of the envelop, as shown in Fig. 7, or in position to enable the folded flap 19-20 to be connected therewith 30 by passing its apertures over the respective ends of the member 32, the barbed end passing through one series of apertures and the socket end passing through the other. The flap 13, together with the diverging folded 35 portion 16-17, is then folded over the sealing flaps 11-12 and the diverging portions 16-17 folded over the folded reduced portions 19-20, with its perforations passed over the protruding arms of the metal fastening device, and the securing of the envelop completed by bending the two arms of the fastening device toward each other and thrusting the barbed end into the socket, as 40 before described, thus disposing the device 45 into the position shown in Fig. 2.

The flap 13 and the edges of the diverging members 16-17 are preferably provided with gumming material, as indicated at 42, so that the parts may be securely connected 50 when closed.

By this means a double securing of the envelop is effected, first by the sealing of the gummed surfaces and second by the metal locking strip. As a still further protection, 55 the exposed portion of the metal strip 32 is provided with characters denoting the amount of postage required to mail the envelop, as indicated in Fig. 2, so that if the member 32 be cut loose and another substituted, the absence of these characters will denote that the envelop has been tampered with.

The portion 10 of the envelop and the metal strip 32 are provided with spaced small apertures 43-45, through which rivet 60 devices 44 may be passed to enable the mem-

ber 32 to be attached immovably to the body of the envelop.

It will thus be obvious that a very simply constructed envelop is produced which effectually prevents the contents from surreptitious handling, and which will indicate to the receiver whether or not the securing means has been tampered with. 70

The envelop may be made of various sizes, and of any suitable material adapted to the 75 purposes for which it is employed.

Having thus described the nature of the invention, what is claimed as new is:-

1. An envelop blank comprising a sheet of paper divided by folding lines into a front 80 portion having sealing flaps at the ends and a back portion extending from one side and a closure portion extending from the other side, said back portion and closure portion being uniform in size with the front portion 85 and with a slit at the juncture of the closure portion and front portion, said back portion having a sealing flap extending from its free edge and of less length than the back portion, whereby an envelop may be formed by 90 folding the back portion over the front portion and folding the end flaps over the back portion and passing the reduced sealing flap through said slit and passing the closure portion with its sealing flap around the folded 95 front and back portions with the reduced sealing flap overlapping the sealing flap of the closure portion.

2. An envelop comprising a sheet of paper divided by folding lines into a front portion 100 having sealing flaps at the ends and a back flap extending from one side and a closure flap extending from the other side and with a slit at the juncture of the closure flap and the front portion said back flap having a reduced sealing flap extending from its free edge and said closure flap having a sealing flap extending from its free edge with the outer portions of said sealing flaps folded upon themselves and cemented, and said front portion and sealing 105 flaps provided with spaced apertures adapted to register when the envelop is in folded position, a metal fastening device having yieldable barbs at one end and a socket having an enlarged interior and adapted to receive and hold said barbs at the other end and adapted to be bent into U-form and thrust through said apertures and the barbed end inserted into the socket after the envelop is closed, to secure the same. 115

3. An envelop formed with a front and back and overlapping sealing flaps provided with registering apertures, and a fastening device formed of a metal member having resilient barbs at one end and a socket having an enlarged interior at the other end and adapted to be looped through said apertures and the barbed end inserted into the socket after the envelop is closed. 120

4. An envelop having front and back por- 130

tions and with overlapping sealing flaps provided with registering apertures, a fastening device comprising a metal member having resilient barbs at one end and a socket having 5 a reduced interior at the other end and adapted to be looped through said apertures and the barbed end inserted into the socket after the envelop is closed, and fastening

devices securing said metal member to said envelop.

In testimony whereof I affix my signature, in presence of two witnesses.

FRANK LESLIE RICHARDSON.
